UNITED STATES PATENT OFFICE.

LEON ABEL CELER LETOMBE, OF LILLE, FRANCE.

GAS OR EXPLOSIVE ENGINE.

SPECIFICATION forming part of Letters Patent No. 726,710, dated April 28, 1903.

Original application filed June 1, 1901, Serial No. 62,696. Divided and this application filed October 15, 1901. Serial No. 78,671. (No model.)

To all whom it may concern:

Be it known that I, LEON ABEL CELER LETOMBE, a citizen of the Republic of France, and a resident of No. 60 Rue de Paris, Lille, in the Republic of France, have invented certain new and useful Improvements in Gas or Explosive Engines, of which the following is a specification.

This application is a division of my application Serial No. 62,696, filed June 1, 1901.

The invention relates to four-cycle engines, and comprises an organization of three cylinders, a central double-acting cylinder and two single-acting axially in line therewith and one at each end thereof, with their closed ends turned toward the central cylinder. The pistons of the three cylinders are rigidly connected, and the power is applied to a single crank-shaft located at one end of the series of cylinders. The end cylinders act as slides, and their open ends being turned outwardly permit of coupling to their pistons any device or piece of mechanism which it may be desired to drive. The distribution systems for the several cylinders are to be so arranged and operated as to produce an effective explosion at each forward and backward stroke of the piston.

The invention also comprises a special construction and arrangement of sleeves for uniting the end cylinders to the central double-acting cylinder in such way as to permit removal of the pistons without disturbing the relation of the rigidly-connected cylinders.

I have not shown distributing systems or mechanisms for supplying the mixture of air and gas to the cylinders or a means for regulating them according to the load or work being done, as these several operations may be accomplished by means of any suitable well-known arrangements for that purpose. I should prefer, however, to use the distributing system shown in the United States Patent No. 634,063 or in my original application of which this case is a division.

The accompanying drawing is a longitudinal section showing so much of the engine as is deemed desirable to illustrate the invention.

M is the central double-acting cylinder,

and N P the single-acting cylinders arranged at the ends thereof. M' N' P' are their respective pistons. They are maintained at fixed distances apart by means of hollow cross-bars K, preferably of cast-iron and acting as piston-rods. They and the pistons are held rigidly together by a bar or bolt T, passing through them and having nuts r applied at its ends at the outer faces of the pistons N' and P'.

The packing for the piston-rods consists of long sleeves F, in which the cross-bars K slide, suitable packing rings or segments being employed. Each sleeve F has at one end a flange 6, by which it may be bolted to the cover or head 7 of the end cylinder. The other end of the sleeve is cylindrical and is introduced through a suitable stuffing-box 9 in the head 8 of the double-acting cylinder. 70 5 5 indicate oil-cups screwed into the sleeves.

By removing the bolts securing the flanges of the sleeve, the heads 7 of the single-acting cylinders, loosening up the stuffing-box 9, and removing the nuts r, as well as the oil-cups, it is apparent that by proper manipulation of the parts the sleeves F may be forced into the double-acting cylinder. The cylinder-heads and pistons may all be removed without disturbing the fixed relation of the cylinders. The cylinders are maintained at fixed distances from each other by shouldered rods 5', passing through bosses 5² on the cylinders. The annular space between the cross-bar K 85 and the rod P is connected by holes l with the interiors of the pistons.

On the outside of each of the pistons of the single-acting cylinders are arranged articulated rods 1 2, acting as supports for the flexible pipes composed of the rigid parts 3 3 and the flexible hose 4 4. Water may enter through the cock R, traverse the hollow pistons and cross-bars, and emerge at S.

The cylinders in the general construction are of an ordinary type, being provided with annular water-circulation chambers, and the connecting sleeves may be provided with similar chambers, as shown.

I claim as my invention—

1. In a gas or explosive engine, the combination of cylinders arranged end to end, an

interposed sleeve entering the head of one cylinder and having a flange adjacent one end for attachment to one of the heads, and a stuffing-box mounted on the other head and 5 through which the other end of the sleeve passes.

2. In a gas or explosive engine, the combination of cylinders placed end to end their pistons united by a hollow cross-bar and a 10 tie-bolt passing through the cross-bar and pistons, a sleeve through which the cross-bar

passes interposed between the adjacent heads of the cylinders and having a flange by which it may be bolted to one of said heads and a stuffing-box applied to the other head and 15 through which the sleeve passes.

In testimony whereof I have hereunto subscribed my name.

LEON ABEL CELER LETOMBE.
